UNITED STATES PATENT OFFICE

155,383

DESIGN FOR A COMBINED ACCELERATOR PEDAL PAD AND HEEL REST

Casper A. Brichtson, Chicago, Ill.

Application August 20, 1948, Serial No. 148,196

Term of patent 14 years

(Cl. D14—6)

To all whom it may concern:

Be it known that I, Casper A. Brichtson, a citizen of the United States, residing at Chicago, in the county of Cook and State of Illinois, have invented a new, original, and ornamental Design for a Combined Accelerator Pedal Pad and Heel Rest, of which the following is a specification, reference being had to the accompanying drawing, forming part thereof.

Fig. 1 is a top plan view of a combined accelerator pedal pad and heel rest, showing my new design.

Fig. 2 is a side elevational view of same.

Fig. 3 is a bottom plan view of same.

Fig. 4 is a transverse sectional view taken along the line 4—4 of Fig. 1.

Fig. 5 is a transverse sectional view taken along the line 5—5 of Fig. 1.

I claim:

The ornamental design for a combined accelerator pedal pad and heel rest, as shown.

CASPER A. BRICHTSON.
